IMPELLER

John J. Kovacs, New York, N. Y.

Application July 12, 1949, Serial No. 104,351

1 Claim. (Cl. 103—115)

1

This invention relates to an impeller or rotating blade for water systems and to a method for making the same.

In conducting water from the street mains to the tops of buildings, it frequently becomes necessary to introduce into the water system of the buildings some means to force the water to the top of the buildings. Known impellers are objectionable either because of the number of parts required in their construction or because of their weight.

It is an object of the instant invention to simplify the construction of impellers of the type described.

A further object is to decrease the cost of construction of water impellers.

Another object is to provide an impeller of such light weight and efficient design as to decrease the cost of operation.

Other objects of the instant invention will become apparent in the course of the following specification.

In the accomplishment of these objectives, the improved water impeller is formed in part from a thin disc of any desired diameter and any suitable material. Around the periphery of the disc are radially directed spaced slots while spaced from the inner end of each slot is a coacting circular opening. For each slot and coacting opening, a blade is formed. Each blade is constituted of a flat body in one edge of which a slit is formed, the slit dividing the body into two substantially equal parts. The outer end of the slit is constricted relative to the inner end and coacts with the circular opening when the inner portion of the slit is fitted over the surface of the disc intermediate the inner end of the slot and the coacting circular opening. When the slotted halves of the blade are pressed together, the parts of the blade adjacent the constricted outer portion are locked into the circular opening with the edge of the blade opposite the slit flush with the periphery of the disc. During the pressing operation, the plane of the blade has a tendency to form other than a right angle with the plane of the disc but by forming a concentric circular protrusion in the disc adjacent the inner ends of the blades, the plane of each blade can always be made to form a substantial right angle with the plane of the disc. A central opening is formed in the disc and internally threaded for attachment to the shaft of a prime mover.

The invention will appear more clearly when taken in conjunction with the accompanying

2

drawings, showing by way of example a preferred embodiment of the improved impeller.

In the drawings:

Figure 1 is a plan view of the impeller constructed in accordance with the principles of this invention.

Figure 2 is a sectional view along the line 2—2 of Figure 1, and enlarged.

Figure 3 is a plan view of the impeller blank.

Figure 4 is a plan view of the impeller blade.

Referring now in greater detail to the drawings where like reference numerals indicate like parts, reference numeral 10 indicates the improved impeller.

15 The impeller 10 is constituted of the disc 11 (Fig. 3) and the blade 12 of brass, plastic, or other suitable material. The disc may be of any size desired with the center 13 extruded and internally threaded for attachment to the shaft of the prime mover (not shown) and, of course, could be merely an internally threaded circular opening if desired.

20 Around the periphery of the disc 11 are the spaced and radially directed slots 14 which have substantially equal depth and a width approximately equal to the thickness of the later described blades 12 which are fitted therein. Equally spaced from the inner end of each slot is a coacting circular opening 15, the center of which 25 is on a radius 23 of the disc which substantially bisects the slot, the coacting slot and opening providing a means for attaching the blades to the disc as later shown.

25 The blades 12 may have an outer periphery of any desired shape as long as adapted to the impeller housing which is not shown. In one edge 18 of each blade 12 is a slit 16 which coacts with the previously mentioned slot and circular opening and substantially divides the 30 blade into two equal parts. The depth of each slit 16 between the points 19 and 20 (Fig. 4) is equal to the distance between the point 21 (Fig. 3), that is the inner end of the slot 14, and the point 22 on the circumference of the circular 35 opening 15, the point 22 being on the radius 23 of the disc which passes through the center of the circular opening and substantially bisects the slit 14. Otherwise expressed, the depth of each slit 16 is equal to the distance between the 40 inner end of the slot 14 and the center of the coacting circular opening plus the radius of the opening. The outer end of the slit 16, between the points 19 and 24, is constricted as shown in Figure 4 for a distance substantially equal 45 to the diameter of the circular opening so that 50

55 to the diameter of the circular opening so that

the depth of the slit 16 between the points 20 and 24 (Fig. 4) is substantially equal to the distance between the points 21 and 25 (Fig. 3) on the disc.

The operation in forming the impeller 10 is as follows:

The disc 11 with the radially directed slots 14 and coaxing central openings 15 is die stamped from a sheet of suitable material. While not essential, the blades 12 can also be stamped from the sheet along with the disc in order to save both time and material and the only prerequisite for which is the proper die which has been constructed by applicant. During the stamping operation, each blade has a slit 16 formed therein, the dimensions and shape of which have been previously described. With the plane of a blade reasonably perpendicular to the plane of the disc, the slit 16 is fitted into one of the slots 14 until the constricted outer end of the slit 16, between the points 19 and 24, is over the coaxing circular opening 15 of the disc, the diameter of the opening 15 being approximately equal to the length of the constricted portion of the slit 16, that is between the points 19 and 24. By squeezing together the opposite edges of the slotted portions of the blade so assembled, the opposed edges of said portions are forced into and locked in the opening 15. The squeezing operation alone, however, would tend to move the plane of the blade 12 out of the desired perpendicular position relative to the plane of the disc 11. However, by raising a concentric ring 17 in the disc 11 adjacent the inner ends of the blades, it has been found possible to maintain the plane of each blade substantially perpendicular to the plane of the disc.

With the impeller thus formed and with a coaxing housing (not shown) in which the impeller is inserted to rotate in the direction of the desired flow of the water connected in the pipe line of the water system a simple, effective, and efficient device has been created.

It will be understood that the invention is not limited to the exact disclosure herein described but may lend itself to a variety of expressions within the scope of the appended claim.

What is claimed is:

An impeller for liquids in conduits, the impeller comprising a disc, the disc having radially directed spaced slots formed in the periphery thereof, the slots being of substantially equal depth and width, the disc further having formed therein a circular opening in spaced relationship with each slot, the center of each circular opening being on a radius of the disc substantially bisecting the slot, the circular openings further being of substantially equal diameter with the centers equally spaced from the slots; the impeller further comprising a blade for each slot and circular opening, each blade having a length substantially equal to the distance between the center of the circular opening and the periphery of the disc plus the radius of the opening as measured on the radius of the disc bisecting the slot, each blade further having a thickness substantially equal to the width of the slots and being divided into two substantially equal parts by a slit formed in one edge, the outer portion of the slit being constricted relative to the inner portion for a distance substantially equal to the diameter of the circular opening, the slit further having a depth substantially equal to the distance between the end of the slot and the center of the circular opening plus the radius of said opening as measured on the radius of the disc bisecting the slot, the disc further having a ring formed therein, the ring being concentric with and inwardly spaced from the circular openings.
